G. G. GOING

TYPEWRITING MACHINE

Filed March 5, 1927

UNITED STATES PATENT OFFICE.

GEORGE G. GOING, OF MIDDLETOWN, CONNECTICUT, ASSIGNOR, BY MESNE ASSIGNMENTS, TO REMINGTON TYPEWRITER COMPANY, A CORPORATION OF NEW YORK.

TYPEWRITING MACHINE.

Application filed March 5, 1927. Serial No 173,074.

My invention relates to typewriting and like machines and more particularly to line spacing mechanism therefor.

The main object of the invention, generally stated, is to provide comparatively simple, yet highly effective, mechanism of the character specified in which provision is made for assuring an engagement of the line spacing pawl with the proper tooth of the line spacing wheel in accordance with the setting of the line space regulating device, and in which effective means are provided for preventing overthrow of the line spacing wheel and platen.

To the above and other ends which will hereinafter appear my invention consists in the features of construction, arrangements of parts and combinations of devices set forth in the following description and particularly pointed out in the appended claims.

In the accompanying drawings, wherein like reference characters indicate corresponding parts in the different views:

Figure 1 is a detail, fragmentary, top plan view of one end of a typewriter carriage shown equipped with the devices of my invention.

Figure 2 is a detail, fragmentary, perspective view of the line spacing wheel, its detent and some of the associated parts.

Figure 3 is an end view of the construction represented in Fig. 1, with parts broken away.

Figure 4 is a fragmentary, detail sectional view showing some of the parts represented in Fig. 2; the section being taken on the line 4-4 in Fig. 1 and looking in the direction of the arrows at said line.

Figure 5 is a detail, bottom plan view showing the returning spring for the line spacing lever together with the housing for the spring and the manner of connecting it to said lever, etc.

Figure 6 is an enlarged, detail, side view of the line space regulating device and the guard member carried thereby.

Figure 7 is a detail, fragmentary sectional view taken on the line 7-7 of Fig. 1 and looking in the direction of the arrows at said line.

The present invention is in the nature of

an improvement on the construction disclosed in my Patent No. 1,606,362 dated Nov. 9, 1926.

I have shown my invention in the present instance embodied in the carriage of a Remington-Noiseless machine in which the invention may be readily embodied without modifying, or materially modifying, existing structural features thereof. It should be understood, however, that the invention is not restricted to use in such machines but may be employed in typewriting and like machines generally, wherever found available.

The carriage comprises two end plates, only one of which, the left-hand end plate 1, is shown. These end plates have bearing openings to receive the supporting means for a cylindrical platen 2.

A supporting bracket 3 is detachably fixed on and supported by the end plate 1, as disclosed in my patent hereinbefore referred to, and constitutes a support for certain of the line spacing devices as will hereinafter appear.

A line spacing wheel 4 is connected to the platen by a clutch (not shown) which is controlled by a finger wheel 5. Coacting with the teeth of the line spacing wheel and arranged on top of the latter is a spring-pressed 80 detent roller 6, supported on a spindle 7 carried by a detent carrier, designated as a whole by the reference numeral 8. This carrier is preferably made of sheet metal and the main body portion thereof is preferably substantially U-shaped in cross section to provide side supporting arms for the spindle 7. These arms at the rear ends thereof are apertured to receive a bearing sleeve 9 on which the carrier is mounted for pivotal movement 85 toward and away from the line spacing wheel. The stem of a headed screw 9^a passes through said bearing sleeve 9 and is received at its threaded end in a tapped opening in the left-hand end of a tie rod α , usually employed to connect the end plates of the carriage. The bearing sleeve 9 is of greater length than the distance between the outer sides of the parallel arms of the carrier 8. When, therefore, the screw 9^a is tightened it will cause the 90 sleeve to be firmly held between the head of the screw and the end plate 1 without, how-

100

ever, exerting any binding action on the carrier 8 which is free to turn on the bearing sleeve 9.

A coiled contractile spring 10 is connected at one end to a pin 11 which extends between the side arms of the detent carrier. The other end of this spring is connected to an arm 12 mounted for pivotal adjustment around the stem of a headed screw 13 by which an arm 3^a of the bracket 3 is secured to the end plate 1. The stem of the screw 13 passes through an opening in the arm 12 and through collars 14 arranged on opposite sides of said arm. By tightening the screw 13 the arm 12 is firmly held in the position to which it may be adjusted. This provides a simple means by which the force of the spring exerted on the detent carrier may be adjusted at will.

One of the side arms of the detent carrier 8 is extended forward of the detent roller, as shown, to provide a forward extension 15 having an upper contact edge 16 which is inclined to provide a cam-like bearing surface. It will be seen that the carrier 8 is substantially horizontally disposed and extends from its rear pivoted end to the forward free end over the line spacing wheel, the arm 15 being at a higher elevation than but off-set to one side of said wheel. When the line spacing devices controlled by the usual line spacing lever are actuated, a part thereof, at the last portion of the stroke, will engage the inclined contact edge 16 of the carrier and forcibly wedge the detent roller down into engagement with the teeth of the line spacing wheel thereby preventing an overthrow of said wheel and the platen connected therewith, as will hereinafter more clearly appear. It will be understood that at this time the carrier 8 acts in the nature of a comparatively long lever carrying the detent roller 6 intermediate the ends thereof to effectively hold the detent roller against the wheel and prevent overthrow thereof. the pivot of the carrier and the part engaging the free end of the carrier effectively resisting both a longitudinal movement of the carrier and a lateral movement thereof away from the line spacing wheel.

The means by which the line spacing wheel is turned step by step comprises, in the present instance, a line spacing pawl 17 pivoted at one end on a headed, shouldered pivot screw 18 received at its threaded end in a tapped opening in a supporting ear 19. As more clearly shown in Fig. 7, the outer end of the screw 18 extends beyond the ear 19 and receives a shouldered nut 20 which acts as a lock nut for the screw 18. The cylindrical hub 21 of this nut constitutes an abutment, contact or locking member which coacts with the contact edge 16 on the detent carrier 8 when the line spacing pawl 17 reaches the end of its line spacing movement, as indicated in dotted lines in Fig. 4. This locks the detent carrier and detent against movement away

from the line spacing wheel and firmly holds the latter against overthrow.

The supporting ear 19 for the line spacing pawl is formed integral with and projects upwardly from one edge of a slide 22 that is supported for fore and aft rectilinear movement on the bracket 3. The slide 22 is slotted at 23 to receive the stem of a headed guide screw 24 received at its threaded end in a tapped opening in the bracket. An off-set arm of the slide is connected forward of the ear 19 with an arm 25 of an angular line space lever 26. The connection between the line spacing lever and slide is best shown in Fig. 5, from which it will be seen that a depending pin 27 in the lever arm 25 enters a short slot 28 in the slide 22. This same pin 27 constitutes means for firmly connecting an upstanding post 29 to the lever arm 25. This post, after a slight extent of lost motion of the arm 25 relatively to the slide 22 (due to the pin and slot connection 27—28) will coact with the edge 30 of the pawl above the pivot 18 thereof, and tends to hold the pawl against accidental upward displacement. The line spacing lever which is made of two connected parts is pivoted on a shouldered pivot screw 31 threaded into the bracket 3 and firmly held in place by a lock nut 32, as shown in Fig. 5. A depending pin 33 on the lever arm 25 passes through a slot 34 in the bracket and is connected to one end of a coiled returning spring 35. The opposite end of this spring is connected to an upwardly extending pin 36 carried by a sheet metal housing 37 for the spring. This housing is substantially U-shaped in cross section, and from one of the side arms extends an integral foot piece 38 supported against the bottom wall of the bracket and held in place by the nut 32. The line spacing lever includes a forwardly projecting arm 39 which terminates in a finger piece (not shown) by which the lever and the parts controlled thereby may be actuated as the carriage is returned to the right. This arm with its bearing portion is connected to the arm 25 by a screw 40.

Provision is made for regulating the point in the throw of the line spacing pawl 17 where it is permitted to engage the line spacing wheel, thus determining the extent of movement transmitted to said wheel. In the present instance the construction includes a line space regulating device 41 in the nature of a substantially horizontally disposed arm that extends fore and aft of the machine. The line spacing pawl 17 carries a laterally projecting pin 42 which extends over and is adapted normally to bear on the upper contact edge 43 of the regulating device and along which the pin is adapted to slide. The regulating device normally holds the pawl out of engagement with the line spacing wheel but allows the pawl to engage the wheel at different points in the throw of the pawl

depending on the adjustment of the regulating device. Said regulating device is pivoted at its rear end on a pivot screw 44 supported by an arm 45 on the bracket 3. The lower edge of the regulating device is provided with three locking notches 46, 47 and 48. A depending arm 49 on the bracket 3 has pivoted at the lower end thereof, as at 50 (Fig. 3), a controlling member or arm 51 that extends 10 up at substantially right angles to the regulating member 41. The upright arm 51 carries a laterally projecting pin 52 which engages in any one of the three locking notches 46, 47 and 48, depending on the fore and aft 15 adjustment of the controlling arm 51. This adjustment of the controlling arm determines the height to which the line space regulating arm 41 is adjusted around its pivot 44, and thereby determines whether the line spacing 20 wheel will be moved the extent of one, two or three teeth thereof at each actuation of the line spacing pawl. In order to facilitate an adjustment of the controlling arm 51 I have provided it with an upwardly extending integral finger piece 53 which may be conveniently grasped by the operator to shift the arm 51 and the parts controlled thereby. I also have provided indicating means in order 25 to indicate to the operator whether the mechanism is set for a line feed of one, two or three 30 teeth of the wheel.

Such indicating means comprises a flange 54 formed as a part of the arm 51 and having indices "1", "2" and "3" on the upper side 35 thereof. One or another of these indices will register with the overlying pin 42 on the line spacing pawl, in accordance with the setting of the arm 51 for line spacing of one, two or three teeth of the wheel as in my prior construction.

By my present invention I have provided improved means for insuring the engagement of the line spacing pawl with the proper tooth of the wheel at each actuation of the pawl, 45 in accordance with the setting of the line space regulating device 41 for a one, two or three teeth movement of the wheel, and not permit a faulty operation by engagement of the wheel which would result in an improper 50 line space. Such means comprises what I term a guard member in the nature of an arm 55 pivoted at one end, as at 56 preferably to the line space regulating arm 41. The main body of the arm 55 is off-set from the pivoted 55 portion thereof, so as to overlie the contact edge 43 of the regulating device. The lower edge 57 of the guard arm gradually slopes towards the member 41 as the rear free end of the guard arm is approached. The pin 42 on 60 the line spacing pawl underlies the guard arm and the latter prevents said pin from moving off the edge 43 in the rapid operation of the pawl, as will presently appear. It will be seen that the guard member 55 is in the 65 nature of an angular lever, the depending arm

58 of which is connected to one end of a contractile spring 59 whose force is directed out of line with the pivot 56 of the member 55. The lower end of this spring is connected to a suitable point, as to an arm 60 on the controlling member or arm 51. This spring has a two-fold function. It acts on the guard member 55, 58 and through the latter tends to press the pin 42 down on the contact edge 43 of the line space regulating member, and as the pin 42 advances along said contact edge it forces the free end of the guard arm up against the force of the spring 59, thus preventing the pin 42 in a rapid operation of the pawl from moving off the edge 43 of the regulating member. Consequently the pawl will be accurately guided and caused to engage the proper tooth of the line space wheel irrespective of the position of adjustment of the regulating device 41. By reason of the fact that the guard member 55, 58 is carried by and adjusted with the regulating device 41 in the adjustment of the latter, said guard member will always bear the same normal relation to the pin 42 and always be positioned to accurately coat therewith.

The second function of the spring 59 is to hold the member 41 down in engagement with the locking pin 52 so as to act as a spring detent thereon, and by means of the interlocking engagement between the controlling member 51 and regulating device 41, both will be held by the spring 59 in any one of the three positions to which they may be adjusted.

Various changes may be made in the construction, and some of the parts may be employed without others, without departing from my invention as it is defined in the following claims.

What I claim as new and desire to secure by Letters Patent, is:

1. In a typewriting machine, the combination of a line spacing wheel, a line spacing pawl coacting with said wheel to effect an intermittent step-by-step forward feed of the platen, an adjustable line space regulating device on which said pawl normally rests and on which it has a sliding movement in its line spacing operation, and an overlying arm that holds the pawl against accidental displacement from said regulating device without interfering with the return movement of said pawl independently of the wheel after each line spacing movement is effected.

2. In a typewriting machine, the combination of a line spacing wheel, a line spacing pawl, an adjustable line space regulating device on which said pawl normally rests and on which it has a sliding movement in its line spacing operation, and an overlying spring-pressed arm coacting with said pawl and exerting its spring force against the pawl to prevent an accidental displacement thereof from said regulating device.

3. In a typewriting machine, the combina-

tion of a line spacing wheel, a line spacing pawl, coacting with said wheel to effect an intermittent step-by-step forward feed of the platen, an adjustable line space regulating device on which said pawl normally rests and on which it has a sliding movement in its line spacing operation, and an overlying guide member that coacts with said pawl to maintain it against accidental displacement off said regulating device without interfering with the return movement of said pawl independently of the wheel after each line spacing movement is effected, said guide member being carried by and adjustable with said regulating device.

4. In a typewriting machine, the combination of a line spacing wheel, a line spacing pawl, an adjustable line space regulating device on which said pawl normally rests and on which it has a sliding movement in its line spacing operation, an overlying arm that holds the pawl against accidental displacement from said regulating device, a single spring, and means by which said spring tends to hold said regulating device in adjusted position and said arm in effective position.

5. In a line space mechanism for typewriting or like machines the combination of a line spacing pawl, an adjustable spring-pressed line spacing regulating device on which the pawl normally rests and on which it has a sliding movement in its line spacing operation, a separate hand-controlled member coacting with said regulating device to control its adjustment, a pin, a series of pin-engaging notches between said regulating device and hand controlled member, whereby an adjustment of the hand-controlled member will adjust the regulating device to different line determining positions and the regulating device will act as a spring detent to hold the hand-controlled member against accidental displacement from the line determining position to which it may be adjusted, and an overlying arm that holds the pawl against accidental displacement from said regulating device.

6. In a line space mechanism for typewriting or like machines, the combination of a line spacing pawl, an adjustable spring-pressed line spacing regulating device on which the pawl normally rests and on which it has a sliding movement in its line spacing operation, a separate hand-controlled member coacting with said regulating device to control its adjustment, a pin, and a series of pin-engaging notches between said regulating device and hand-controlled member, whereby an adjustment of the hand-controlled member will adjust the regulating device to different line determining positions and the regulating device will act as a spring detent to hold the hand-controlled member against accidental displacement from the line determining posi-

tion to which it may be adjusted, and a guide member that coacts with said pawl to maintain it against accidental displacement off said regulating device, said guide member being carried by and adjustable with said regulating device.

7. In a line space mechanism for typewriting or like machines, the combination of a line spacing pawl, an adjustable spring-pressed line spacing regulating device on which the pawl normally rests and on which it has a sliding movement in its line spacing operation, a separate hand-controlled member coacting with said regulating device to control its adjustment, a pin, a series of pin-engaging notches between said regulating device and hand-controlled member, whereby an adjustment of the hand-controlled member will adjust the regulating device to different line determining positions and the regulating device will act as a spring detent to hold the hand-controlled member against accidental displacement from the line determining position to which it may be adjusted, an overlying spring-pressed arm coacting with said pawl and exerting its spring force against the pawl to prevent an accidental displacement thereof from said regulating device, the spring of said arm also exerting its force on said regulating device and causing it to act as a detent as stated.

8. In a line space mechanism for typewriting or like machines, the combination of a line spacing wheel, a line spacing pawl, a spring-pressed pivoted line space regulating device on which the pawl normally rests and has a sliding movement in its line spacing operation, the position of the regulating device in turning on its pivot determining the point in the throw of the pawl where it engages the line spacing wheel, a separate hand-controlled member pivoted to turn in an arc at an angle to the arc through which the pivoted regulating device turns and coacting with said regulating device to control its pivotal adjustment, the regulating device coacting with said hand-controlled member to operate as a spring detent to hold it against accidental displacement from the line spacing determining positions to which it may be adjusted, an arm pivoted on said regulating device and overlying said pawl to prevent an accidental displacement thereof from said regulating device, and a single spring connected to said arm and also exerting its force on the regulating device to cause it to act as a spring detent as stated.

9. In a typewriting or like machine, the combination of a line spacing wheel, a pivoted line spacing pawl that extends longitudinally in one direction from its pivot, an overlapping pivoted line space regulating arm that extends from its pivot in the opposite direction and on which the pawl slides

- in its line spacing movement, hand-controlled means for adjusting said regulating arm to different set positions around its pivot and thereby determine the extent of line spacing, 5 and an overlying member carried by and adjustable with said line space regulating arm and coacting with said pawl to prevent an accidental displacement thereof from said regulating arm.
- 10 10. In a typewriting or like machine, the combination of a line spacing wheel, a line spacing pawl, a pivoted adjustable line space regulating arm on which said pawl normally rests and on which it has a sliding movement 15 in its line spacing operation, a guard member comprising an angular lever pivoted to and adjustable with said regulating arm, one arm of said angular lever coacting with said pawl to prevent an accidental displacement 20 thereof from said regulating arm, and a spring connected to the other arm of said angular lever and also exerting its force to hold the regulating arm in its adjusted position.
- 25 11. In a line space mechanism for typewriting or like machines, the combination of a line spacing pawl, an adjustable spring-pressed line spacing regulating device on which the pawl normally rests and has a sliding movement in its line spacing operation, a separate hand-controlled member coacting with said regulating device to control its adjustment, a pin, and a series of pin-engaging notches between said regulating device 30 and hand-controlled member, whereby an adjustment of the hand-controlled member will adjust the regulating device to different line determining positions and the regulating device will act as a spring detent to hold the 35 hand controlled member against accidental displacement from the line determining position to which it may be adjusted, a guard member pivoted on said regulating device and coacting with said pawl to prevent an accidental displacement thereof from the regulating device, and a spring connected to said 40 guard device to hold it in effective position and also exerting its force to maintain an interlocking engagement between said pin 45 and engaging notches.
- 50 12. In a typewriting or like machine, the combination of a line spacing wheel, a detent roller cooperative with said wheel on the top thereof, a substantially horizontally disposed spring pressed carrier for said detent roller, said carrier being in the nature of a lever pivoted at one end and with a forwardly projecting substantially horizontally disposed arm thereof carrying a cam, a line spacing pawl, a slide on which said pawl is mounted, a line spacing lever for moving said slide, and an abutment on said slide brought into engagement with said cam and overlying said arm at the last part of each line spacing operation to hold the carrier and de- 55 tent roller against upward displacement away from the line spacing wheel and thereby prevent an overthrow thereof.
13. In a typewriting or like machine, the combination of a line spacing wheel, a detent roller therefor, a lever-like sheet metal carrier for said detent roller, said carrier being pivoted at one end and substantially U-shaped in cross-section at its body portion, a contractile spring connected at one end to said carrier, adjustable means connected to the other end of said spring for varying the force of said spring on said carrier, a rigid extension on the carrier, a line spacing lever, an engaging member connected with said line spacing lever and moved thereby at the last part of the line spacing operation into contact with the extension on the carrier to hold the detent roller in engagement with the line spacing wheel and thus prevent overthrow thereof. 75
14. In a typewriting or like machine, the combination of a line spacing wheel, a detent roller therefor, a lever-like detent roller carrier pivoted at one end and carrying said roller intermediate its ends, the free end portion of said lever-like carrier having an inclined contact face, a line spacing lever, and an engaging member controlled thereby and moved at the last part of the line spacing operation into engagement with said inclined face to hold the carrier and detent roller against releasing movement and thus prevent an overthrow of the line spacing wheel. 80
15. In a typewriting or like machine, the combination of a line spacing wheel, a detent roller bearing on the top thereof, a substantially horizontally disposed lever-like detent roller carrier pivoted at its rear end and carrying said roller intermediate the ends thereof, the free forward end portion of said carrier having an inclined contact face, a line spacing lever, a slide movable fore and aft of the machine by said line spacing lever, a line spacing pawl carried by said slide, and an engaging member carried by said slide and cooperative at the last part of the line spacing operation with said inclined face to hold the carrier and detent roller against releasing movement and thus prevent an overthrow of the line spacing wheel. 85
16. In a typewriting or like machine, the combination of a line spacing wheel, a detent roller therefor, a sheet metal carrier for said roller substantially U-shaped in cross section and pivoted at one end and having one of its side arms extended to provide an engageable arm at the free end of the carrier, the detent roller being pivoted on the carrier intermediate its ends and between the side arms thereof, a line spacing lever, and a contact device moved thereby at the last part of the line spacing operation into engagement with said engageable arm of the carrier to prevent a release of the detent roller. 90
17. In a typewriting or like machine, the combination of a line spacing wheel, a detent roller therefor, a lever-like sheet metal carrier for said roller substantially U-shaped in cross section and pivoted at one end and having one of its side arms extended to provide an engageable arm at the free end of the carrier, the detent roller being pivoted on the carrier intermediate its ends and between the side arms thereof, a line spacing lever, and a contact device moved thereby at the last part of the line spacing operation into engagement with said engageable arm of the carrier to prevent a release of the detent roller. 95
18. In a typewriting or like machine, the combination of a line spacing wheel, a detent roller therefor, a lever-like sheet metal carrier for said roller substantially U-shaped in cross section and pivoted at one end and having one of its side arms extended to provide an engageable arm at the free end of the carrier, the detent roller being pivoted on the carrier intermediate its ends and between the side arms thereof, a line spacing lever, and a contact device moved thereby at the last part of the line spacing operation into engagement with said engageable arm of the carrier to prevent a release of the detent roller. 100
19. In a typewriting or like machine, the combination of a line spacing wheel, a detent roller therefor, a lever-like sheet metal carrier for said roller substantially U-shaped in cross section and pivoted at one end and having one of its side arms extended to provide an engageable arm at the free end of the carrier, the detent roller being pivoted on the carrier intermediate its ends and between the side arms thereof, a line spacing lever, and a contact device moved thereby at the last part of the line spacing operation into engagement with said engageable arm of the carrier to prevent a release of the detent roller. 105
20. In a typewriting or like machine, the combination of a line spacing wheel, a detent roller therefor, a lever-like sheet metal carrier for said roller substantially U-shaped in cross section and pivoted at one end and having one of its side arms extended to provide an engageable arm at the free end of the carrier, the detent roller being pivoted on the carrier intermediate its ends and between the side arms thereof, a line spacing lever, and a contact device moved thereby at the last part of the line spacing operation into engagement with said engageable arm of the carrier to prevent a release of the detent roller. 110
21. In a typewriting or like machine, the combination of a line spacing wheel, a detent roller therefor, a lever-like sheet metal carrier for said roller substantially U-shaped in cross section and pivoted at one end and having one of its side arms extended to provide an engageable arm at the free end of the carrier, the detent roller being pivoted on the carrier intermediate its ends and between the side arms thereof, a line spacing lever, and a contact device moved thereby at the last part of the line spacing operation into engagement with said engageable arm of the carrier to prevent a release of the detent roller. 115
22. In a typewriting or like machine, the combination of a line spacing wheel, a detent roller therefor, a lever-like sheet metal carrier for said roller substantially U-shaped in cross section and pivoted at one end and having one of its side arms extended to provide an engageable arm at the free end of the carrier, the detent roller being pivoted on the carrier intermediate its ends and between the side arms thereof, a line spacing lever, and a contact device moved thereby at the last part of the line spacing operation into engagement with said engageable arm of the carrier to prevent a release of the detent roller. 120
23. In a typewriting or like machine, the combination of a line spacing wheel, a detent roller therefor, a lever-like sheet metal carrier for said roller substantially U-shaped in cross section and pivoted at one end and having one of its side arms extended to provide an engageable arm at the free end of the carrier, the detent roller being pivoted on the carrier intermediate its ends and between the side arms thereof, a line spacing lever, and a contact device moved thereby at the last part of the line spacing operation into engagement with said engageable arm of the carrier to prevent a release of the detent roller. 125
24. In a typewriting or like machine, the combination of a line spacing wheel, a detent roller therefor, a lever-like sheet metal carrier for said roller substantially U-shaped in cross section and pivoted at one end and having one of its side arms extended to provide an engageable arm at the free end of the carrier, the detent roller being pivoted on the carrier intermediate its ends and between the side arms thereof, a line spacing lever, and a contact device moved thereby at the last part of the line spacing operation into engagement with said engageable arm of the carrier to prevent a release of the detent roller. 130

and an overthrow of the line spacing wheel.

17. In a typewriting or like machine, the combination of a line spacing wheel, a detent roller therefor, a pivoted carrier for said roller a coiled spring connected at one end to said carrier, a pivoted arm to which the other end of said spring is connected, and a combined pivot and binding screw on which

said arm is mounted, said screw holding said arm in the different positions to which it may be adjusted around its pivot, to vary the force exerted by said spring against said carrier. 10

Signed at Middletown, in the county of Middlesex and State of Connecticut, this 28th day of February, A. D. 1927.

GEORGE G. GOING.
